CLAIM

(62) Division of application No. 29/688,119, filed on Apr. 18, 2019, now Pat. No. Des. 899,943.

The ornamental design for an actuator for an aerosol bottle for dispensing a foam hair care composition, as shown and described.

DESCRIPTION

(51) **LOC (12) Cl.** **09-07**

FIG. 1 is a perspective view of an actuator for an aerosol bottle for a foam hair care composition, embodying our new design;

(52) **U.S. Cl.**

FIG. 2 is a front view thereof;

(58) **USPC** **D9/448**

FIG. 3 is a first side view thereof;

Field of Classification Search

FIG. 4 is a back view thereof;

USPC D9/516-575, 682-694, 434-436,
